UNITED STATES PATENT OFFICE.

JOHN EDW. OGDEN, OF MOUNTAINVILLE, NEW YORK, AND CHARLES C. TOMKINSON,
OF PLAINFIELD, NEW JERSEY; SAID TOMKINSON ASSIGNOR TO SAID OGDEN.

STRUT-DOOR.

1,283,545.

Specification of Letters Patent.

Patented Nov. 5, 1918.

Application filed October 30, 1917. Serial No. 199,276.

To all whom it may concern:

Be it known that we, JOHN EDWARD OGDEN, a citizen of the United States of America, and a resident of Mountainville, town of Cornwall, Orange county, and State of New York, and CHARLES C. TOMKINSON, a citizen of the United States of America, and a resident of Plainfield, Union county, and State of New Jersey, have invented certain new and useful Improvements in Strut-Doors, of which the following is a specification, reference being had to the accompanying drawings, forming a part thereof.

This invention relates to new and useful improvements in doors and especially to large heavy doors such as are used on pier sheds, warehouses and the like, and it relates more specifically to two section doors.

Its object is to provide a simple but strong operating mechanism for such doors which is so arranged that the door is amply supported in all of its positions.

Another object is to provide struts for supporting the door in certain of its open positions and automatically actuated mechanism for moving the struts into the desired supporting relation with the other parts of the apparatus.

In order that our invention may be thoroughly understood we will now proceed to describe the same in the following specification, and then point out the novel features thereof in appended claims.

Referring to the drawings:

Figure 1 is a sectional side elevation of a door made according to and embodying this invention, with the parts shown in the positions they assume when the door is closed.

Fig. 2 is a similar view of the same parts with the door fully open.

Fig. 3 is a vertical sectional plan view of some of the parts shown in the preceding figures, the section being taken on the line 3-3 of Fig. 1.

Fig. 4 is a side elevation of a door having an operating mechanism of still different construction, which is also an embodiment of this invention, the door being shown in its closed condition.

Fig. 5 is a similar view of the structure of Fig. 4 with the door fully open.

Like characters of reference designate corresponding parts in all the figures.

10 designates the side posts and 11 the 55 lintel of a door opening. This is closed by

a door which comprises an upper section 12, and a lower section 13. At the sides of the upper section are guides 14 up into which the lower section slides. Guide rollers 15 are provided at the lower corners of the 60 lower door section, which run upon the door posts 10. Hoisting chains 16 are also connected with these lower corners of the lower door section as for example to the pivots of the guide rollers 15. These chains run up 65 over sheaves 17 on a shaft 18 above the door opening and down to counterweights 19 to which they are affixed. It is to be understood that the shaft 18 extends across the width of the door opening and that above 70 each of the rollers 15 a sheave 17 is affixed thereto. Actuating mechanism for shaft 18 such as a hand chain and suitable gearing is provided, but these are not shown as they are well known and understood and form no 75 part of the present invention.

Pivoted to brackets 20 which are affixed to the sides of the upper door section, are struts 21. On the lower ends of these struts are pivots 22 each of which rotatively supports a pair of guide rollers 23 of like diameter and a sheave 24 of smaller diameter between the rollers. The guide rollers run between vertical guides 25. 26 are flexible elements such as ropes or chains 80 which are affixed to the lower corners of the upper door section at 27, run down under the sheaves 24 and up to stationary anchorages 28 above the door opening.

30 are head chains connected with the 90 upper corners of the upper door section at 31 and to stationary anchorages 32 above the door opening.

Before more specifically describing the structures shown in the other figures of the drawings, we will describe the operation of the apparatus shown in Figs. 1, 2 and 3.

When the sheaves 17 are rotated to raise the hoisting ropes 16, the lower door section 13 will be raised in the guides 14 to a position back of the upper door section 12. Its further movement relative to the upper door section is limited by the pivots of the guide rollers 15. Further upward movement of the hoisting chains will cause the lower edges 105 of both of the door sections to rise vertically. But during this movement the other parts of both door sections will swing inwardly, supported by the struts 21.

In order that the struts properly support 110

the door sections as they swing inwardly, it is necessary that the positions of their lower ends be raised and at the same time supported. This is accomplished by the ropes

5 26. It may be seen that as the lower corners of the door sections rise, the points of rope connection 27 go up with them. This will cause the ropes 26 to raise the sheaves 24 and the lower ends of the struts at one-
10 half the rate of movement of the hoisting chains and will produce the desired result.

The head chains 30 are provided to support the upper ends of the door sections as the weight thereof above the pivotal connections of the struts with the door moves in beyond these pivotal supports and therefore prevent the lower corners of the door sections from overrunning the hoisting chains.

In closing the door this operation is reversed and the lower ends of the struts are lowered automatically by the downward movement of the points 27.

In the arrangement shown in Figs. 4 and 5, the hoisting ropes 40 are connected with the lower corners of the lower door section as in the other case, run over the sheaves 17 on the overhead transverse shaft 18, down under sheaves 41 on counterweights 42 and up to fixed anchorages 43.

30 Another rope 44 is connected with the lower end of each strut 21, up over sheaves 45-46 and to another counterweight 47.

On the shaft 18 is a gear 50 and a rotative arm 51. A gear 52 mounted on this arm is in mesh with gear 50 and 53 is a gear connected with sheave 45. 54 is a pivoted lever connected with the arm 51 by a rod 55. This is provided with a forked portion 56 and a spring 57 is connected therewith and to a fixed point 58, as shown, and 59 is a bracket projecting above the lower door section for actuating the lever 55. A shelf bracket 60 is shown in Fig. 5 for supporting the parts of the door sections in their open position, 45 which overhang their pivotal connections with the struts.

When the shaft 18 is rotated to open the door, the operation of the door sections will be the same as that previously explained. 50 In this case however, when the lower door section reaches the upper end of its vertical movement, the bracket 59 will engage the forked portion 56 of lever 54 and raise it and the arm 51. The spring 57 will complete

55 this movement until gear 52 is brought in mesh with gear 53. The rotation of shaft 18 through the gears described will now be imparted to sheave 45 which will cause the ropes 44 to raise and support the lower ends 60 of the struts during the remainder of the opening movement and support the struts while the door is open.

In closing, the gears remain in mesh and the struts are lowered until the bracket 59 engages the forked part 56 of lever 54 and

pulls it down, which movement is completed by the action of the spring 57.

We have illustrated and described different forms of mechanism which embody this invention in order to show that it is not limited to any specific form of construction and in fact intend no limitations other than those imposed by the appended claims.

What we claim is:

1. A door vertically movable at a certain point thereof and adapted at other points to swing out of a vertical plane, a strut having its upper end pivotally connected to the door to have a supporting action as to said other points, and means for supporting the lower end of the strut, actuated by the vertical movement of said point to move at a lesser degree than they.

2. A door vertically movable at a certain point thereof and adapted at other points to swing out of a vertical plane, struts having their upper ends pivotally connected with the edges of the door to have a supporting action as to said other points, vertical guides for the lower ends of the struts, and means for supporting the lower ends of the struts actuated by the vertical movement of said points to a lesser degree than they.

3. A door vertically movable at certain points thereof and adapted at other points to swing out of a vertical plane, hoisting means connected with said vertical movable points of the door, struts having their upper ends pivotally connected with the edges of the door at other than the vertical movable points thereof to have a supporting action as to said other points, vertical guides for the lower ends of the struts, sheaves on the struts, and flexible elements connected with the vertically movable points of the door running around said sheaves and to an anchorage above the door opening, whereby the vertical movement of said points of the door causes a reduced movement of the lower ends of the struts in the guides.

4. A door having its lower edge arranged to move vertically, and its other parts arranged to swing out of a vertical plane, hoisting means connected with the lower corners of the door, struts having their upper ends pivotally connected with the edges of the door intermediate the height thereof, vertical guides for the lower ends of the struts, sheaves on the lower ends of the struts, flexible elements connected with the lower corners of the door running under the sheaves and to an anchorage above the door opening, whereby the vertical movement of the door causes a reduced movement of the lower ends of the struts in the guides.

5. A door having its lower edge arranged to move vertically and its other parts arranged to swing out of a vertical plane, hoisting means connected with the lower corners of the door, struts having their upper ends

5 pivotally connected with the edges of the door intermediate the height thereof, vertical guides for the lower ends of the struts, pivots on the lower ends of the struts, a pair of guide rollers on each of said pivots, a sheave on each pivot between the guide rollers thereon, flexible elements connected with the lower corners of the door running under the sheaves and to an anchorage above 10 the door opening, whereby the vertical movement of the door causes a reduced movement of the lower ends of the struts in the guides.

6. A door comprising an upper section and a lower section, guide connections between 15 the sections to provide for the lower section being raised up beside the upper section, downwardly extending struts at the sides of the door opening having their upper ends pivotally connected with the sides of the upper section above its lower edge, vertical guides for the lower ends of the struts, means for vertically lifting the lower edges of the door sections in a vertical plane and permitting the other portions of the sections to 20 swing out of the vertical plane, said struts being arranged to have a supporting action as to said other portions of the door sections, and means actuated by the vertical movement of the sections arranged to raise the lower 25 ends of the struts in their guides at a lesser 30 ends of the struts in their guides at a lesser

degree than that of the lower edges of the door sections and to support said struts.

7. A door comprising an upper section, guides thereon, a lower section slidable in said guides, stationary vertical guides for the lower corners of said lower section, downwardly extending struts at the sides of the door opening having their upper ends pivotally connected with the sides of the upper section above its lower edge, vertical guides for the lower ends of the struts, hoisting means connected with the lower corners of the lower section for raising the lower section up into the guides on the upper section and for thereafter raising the lower edges of both sections vertically, permitting the other portions of the sections to swing out of the vertical plane, said struts being arranged to have a supporting action as to said other portions of the door sections, and means automatically actuated by the movement of the two sections arranged to raise the lower ends of the struts in their guides at a lesser degree than that of the lower edges of the door sections.

In witness whereof we have hereunto set our hands this 26th day of October, 1917.

J. EDW. OGDEN.
CHARLES C. TOMKINSON.
